E. F. HAYS AND C. E. GARRISON.
CRANK SHAFT GRINDER.
APPLICATION FILED JULY 7, 1920.

1,376,274.

Patented Apr. 26, 1921.

UNITED STATES PATENT OFFICE.

ELIJAH F. HAYS AND CHARLES E. GARRISON, OF MOUNT VERNON, ILLINOIS.

CRANK-SHAFT GRINDER.

1,376,274.

Specification of Letters Patent. Patented Apr. 26, 1921.

Application filed July 7, 1920. Serial No. 394,598.

To all whom it may concern:

Be it known that we, ELIJAH F. HAYS and CHARLES E. GARRISON, citizens of the United States, residing at Mount Vernon, 5 in the county of Jefferson and State of Illinois, have invented certain new and useful Improvements in Crank-Shaft Grinders, of which the following is a specification.

This invention relates to devices for 10 grinding the bearings of shafts and other bodies, and has for one of its objects to provide a simply constructed implement which may be readily applied to the shaft bearing and by which an unevenly worn 15 or otherwise impaired bearing may be ground "true," and restored to operative shape.

With these and other objects in view, the 20 invention consists in certain novel features of construction as hereinafter shown and described and then specifically pointed out in the claims, and in the drawings illustrative of the preferred embodiment of the invention.

25 Figure 1 is a side elevation partly in section of the improved implement applied,

Fig. 2 is a plan view, and

Fig. 3 is an end elevation of the same,

30 Fig. 4 is a detached perspective view of one of the abrasive members, and its holding plates,

Fig. 5 is a detached perspective view of one of the adjusting blocks,

35 Fig. 6 is a detached perspective view of the feed plate.

The improved device comprises a base member 10 having spaced longitudinal slots 11 and an operating handle 12 attached to or extending from one end.

40 Bearing upon the base member 10 between the slots 11, is a feed plate 13, the latter having a plurality of obliquely directed channels 14 to increase the "grip," and secured to the member 10 in any suitable manner, for instance by bolts 15.

Disposed through the slots 11 are threaded rods or posts 16, the posts having clamp nuts 17 bearing against the lower face of the base member 10. Threaded upon each 50 post 16 and bearing upon the upper face of the member 10, is a relatively thin washer 18, each washer having wings 19 depending into the slots 11 and connected to the posts by pins 20.

55 By this means the posts are held from

turning in the slots, while at the same time adjustable longitudinally of the slots to vary the distance between the posts.

Threaded upon the posts 16 are spacing blocks 21, the threaded apertures of the 60 blocks being at one side of the center, so that by turning the blocks end for end upon the posts, the distance between their contiguous ends may be varied, to fit bearings of different sizes as hereafter explained. 65

An upper or follower member 22 is movably engaged with the posts 16 by longitudinally directed slots 23, and adjustable longitudinally of the posts by nuts 24 and 25, as shown.

Attached to the lower face of the follower member 22 between the posts 16 is an abrading element represented as a whole at 26, the member 26 being reduced at the ends and with outwardly opening slots in 75 the reduced portions, to receive holding screws 27 and washers or templets 28.

The implement is applied by detaching the follower member 22 with its abrading element, and the member 10 disposed with 80 the feed plate 13 against the bearing to be ground, represented conventionally at 29, and the blocks 21 and posts 16 adjusted to bring the blocks against the opposite sides of the bearing.

If the bearing be large, the shorter ends of the blocks will be presented to the bearing, and if the bearing be small the longer ends will be presented to the bearing. The blocks are thus readily adaptable to the size 90 of the bearing and is firmly held from lateral displacement.

The follower member 22 is then applied with the abrading element 26 against the bearing, and the nuts 24-25 operated to 95 cause the element 26 to bear with the requisite pressure against the bearing.

The implement is then rotated around the bearing by force applied to the handle 12, and continued until the abrading element 100 has worn away the uneven portions of the bearing, and "truing" the latter.

The pressure of the abrading element will be increased as required by adjusting the nuts 24 and 25.

The member 13 will preferably be of bronze or the like, to insure the requisite "grip" against the bearing, to insure the proper action.

The member 26 may be of any suitable 110

material, substance or compound, such as abrasive stone, emery, carborundum, axolite, or the like, and after a short time wears hollow and thus increases the wearing surface and improves the action.

The blocks 21 being threaded upon the posts can be adjusted longitudinally thereof by rotating, as nuts, upon the posts, and locked in position thereon by jam nuts 29, 10 and are adjustable longitudinally of the members 11 and 22 by adjusting the posts 16 in the slots 11, and by changing the contiguous ends of blocks 21, and are adjustable laterally by turning them on the posts 15 16 until they are the proper distance from the base member 10.

The implement should be moved longitudinally of the bearing at the same time that it is rotated thereon, to insure uniform 20 action.

The improved device is simple in construction, can be inexpensively manufactured, and operates effectually for the purpose described.

25 The preferred embodiment of the invention is disclosed in the drawings and set forth in the specification, but it will be understood that any modifications within the scope of the claims may be made in the 30 construction without departing from the

principle of the invention or sacrificing any of its advantages.

We claim:

1. An implement of the class described, comprising a base member carrying a feed plate, supporting posts in spaced relation rising from said base member, means for adjusting the posts longitudinally of the base member, supporting blocks carried by said posts, a follower member movably engaging said posts, means for adjusting the follower member on the posts, and an abrading element carried by said follower member. 35 40

2. An implement of the class described, comprising a base member having longitudinally directed slots, posts engaging in said slots and adjustable therein, supporting blocks rotatable on said posts and adjustable longitudinally thereon, a follower member having longitudinally directed slots through which the posts pass, means for clamping said follower member to the posts, and an abrading element carried by the follower member. 45 50 55

In testimony whereof, we affix our signatures hereto.

ELIJAH F. HAYS.
CHARLES E. GARRISON.
